Int. Cl. D9—03

U.S. Cl. D9—184

FIG. 1

FIG. 2

FIG. 3

FIG. 4

FIG. 1 is a perspective view of a packaging container having severably connected container compartments showing my new design;

FIG. 2 is a top plan view;

FIG. 3 is a front elevational view, the rear elevational view thereof being the same; and

FIG. 4 is an end elevational view, the opposite end elevational view thereof being the same.

The container compartments of my packaging container are separable and detachable along the illustrated interrupted lines of severance.

I claim:

The ornamental design for a packaging container having severably connected container compartments, as shown and described.
